UNITED STATES PATENT OFFICE

HENRI BURHENNE, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS

TAPE CONDENSER

Application filed January 4, 1932. Serial No. 584,671.

This invention relates to the machine known as a tape condenser by means of which the web of fibre taken from the carding machine is divided into a series of slivers by a series of endless tapes or by a single continuous endless tape passing around dividing rolls and in which these slivers are carried by the tape runs and passed between leather aprons which act to condense each sliver into a roving. In this type of machine the number of roving ends formed from the web taken from the carding machine depends upon the number of tape runs with which the machine is equipped at the dividing rolls and consequently it has been necessary to change the dividing rolls, the tapes and other features of the machine each time it was desired to vary the number of slivers into which the web or bat was to be divided. Such a change of the machine involving new dividing rolls, an entirely new set of tapes of the required width and other parts entailed large expense not only because of the new parts thus required but because of the time involved in making the change and the loss of production.

It is the object of the present invention to provide a construction in which, without the substitution of any new parts and without the loss of any material amount of time, the tape condenser may produce from a given width of web or bat a given number of roving ends or one-half that number, thus doubling the usefulness of the machine.

The object of the invention is further to produce a tape condenser in which the tape runs of each pair are guided into close proximity as they pass a set of condensing aprons to cause the two slivers carried by these runs to be taken together and condensed into a single roving by the aprons.

These and other objects and features of the invention will appear more fully from the accompanying description and drawings and will be particularly pointed out in the claims.

While the invention may be embodied in any tape condenser, there are two well-known types to which it is particularly applicable. In one type, as usually constructed, there is one tape for each two slivers and this tape passes around both dividing rolls presenting

a sliver on one of its runs to one bank of condensing aprons and another sliver on another of its runs to a second bank of condensing aprons, while the next tape presents a sliver on one of its runs to a third bank of condensing aprons and a second sliver on another of its runs to a fourth bank of condensing aprons. In the other type, the dividing rolls are provided with deep grooves and there is a separate tape presenting a separate sliver to each bank of condensing aprons. A preferred form of the present invention is particularly illustrated in connection with the first type and diagrammatically in connection with the second type.

As the invention is only concerned with certain features of the entire machine and as the general construction and operation of these machines are well known and familiar to those skilled in the art, it is only necessary here to illustrate and describe in detail those features with which the invention is particularly concerned.

In the drawings:

Fig. 1 is a more or less diagrammatic view showing the frame of a four-bank single apron tape condenser of the shallow groove type of dividing rolls with one tape for each two slivers formed from the web or bat.

Fig. 2 is a diagrammatic representation of the arrangement in a four-bank single apron tape condenser having the deep grooved type of dividing rolls with one tape for each sliver.

Fig. 3 is a rear elevation partially broken away disclosing a construction embodying the present invention with the tapes mounted and guided to produce a single roving from each pair of slivers.

Fig. 4 is a view similar to Fig. 3 showing a slightly different construction embodying the invention.

Fig. 5 is a detail of a means for positioning the tapes as required by the present invention.

Fig. 6 is a perspective view showing the process of combining and condensing two slivers taken from two proximate runs of tape into a single roving end.

The machine illustrated comprises suitable

side frames 1 upon and in which are mounted the various rolls required. At the front of the machine are the two dividing rolls 2 and 3. These rolls as usual are of iron and provided with grooves each of the width of a tape and with each groove separated by the width of a tape and with the grooves of the one roll alternating with the grooves of the other roll. Four banks of condensing aprons are indicated at 4, 5 and 6, 7 and 8, 9 and 10, 11, respectively. These aprons as usual are endless leather aprons and are driven so that their opposed runs travel rearward and are reciprocated endwise in the familiar manner. Consequently, a sliver fed into the front end of each pair of aprons is rolled and condensed as it is fed forward to produce a roving end. The roving ends delivered from the condensing aprons pass as usual on to spools, one of which is shown at 16. These spools are rotated by friction rolls 12, 13, 14, and 15.

The endless tapes which pass around the dividing rolls 2 and 3 are guided in their course by suitable idler rolls 17 to 26, inclusive.

At each side of the machine relatively wide tapes 27 are employed to separate and carry away the irregular edges of the web. The remainder of the web is separated by the other tapes into slivers which are subsequently condensed into the roving ends.

One tape passes at 28 into the groove of the dividing roll 2, thence at 29 onto the opposed ridge of the dividing roll 3, thence around the idler 23, is given a half twist at 30, thence passes at 31 around the rolls 24, 25, and 26, then returns at 32 to a groove in the dividing roll 3, thence passes at 33 around the opposed ridge of the dividing roll 2, thence around the idler 18, then is given a half twist at 34, thence passes at 35 around the rolls 20 and 19, is given a half twist at 36 and returns to the point where it started at 28. The next tape to the right follows a similar course excepting that in the upper half of the machine it runs at 37 around the three rolls 21, 20, and 19, and at the lower half of the machine from the idler 23 at 38 around the rolls 25 and 26.

The bat or web 39 stripped from the carding machine by the doffer comb 40 enters between the dividing rolls 2 and 3 and is separated into slivers, one sliver being carried by each of the diverging runs 29 and 33 of the first tape between these runs and the ridges of the dividing rolls and the other slivers being carried in a similar manner by the diverging runs of the other tapes.

In the usual construction, each tape run diverging from each dividing roll carries a sliver and the sliver carried by each tape run which passes around the rolls 20 and 19 is delivered to the bank of aprons 4, 5, the sliver carried by each tape run passing around the

rollers 21, 20 and 19 is delivered to the bank of aprons 6, 7, the sliver carried by each tape run passing around the rolls 24, 25, and 26 is delivered to the bank of aprons 8, 9, and the sliver carried by each tape run passing around the rollers 25 and 26 is delivered to the bank of aprons 10, 11.

In the present invention the runs of all the tapes which diverge in one direction, for example, upward, from the dividing rolls pass adjacent a single pair of condensing aprons so as to deliver their slivers thereto and the runs of all the tapes which diverge in the other direction from the dividing rolls, for example, downward, pass adjacent another single pair of condensing aprons so as to deliver their slivers thereto. This result may be secured in the ordinary type of tape condenser illustrated simply by bodily adjusting the base of condensing aprons 6, 7 and 8, 9 rearward on the frame of the machine, as shown in Fig. 1, so that their forward ends will not be in position to take the slivers from the tapes. Consequently it will be seen that all the slivers carried by the tape runs at the top of the machine will be delivered to the bank of aprons 4, 5 and all the slivers carried by the tape runs at the bottom of the machine will be delivered to the bank of aprons 10, 11.

Furthermore, in the present invention means are provided for guiding the runs of each pair of tapes into close proximity as they pass the pair of condensing aprons to which they deliver their slivers. Various means may be provided for bringing the runs of tapes thus into close proximity. In Figs. 1 and 3 the rolls 20 and 25 are grooved at such intervals as to receive the tape runs passing respectively around the rolls 20 and 19 and around the rolls 25 and 26. The journals of these two grooved rolls 20 and 25 are longitudinally adjustable in the machine frame and to provide the desired construction each of these rolls is longitudinally adjusted into the position shown in Fig. 3 so that the runs of tape carried by the grooves thereof are moved over laterally into close proximity to the other set of runs of tapes. A suitable adjustment for this purpose is shown in Fig. 5 in connection with the roll 20. The journal 41 of this roll 20 extends through a bearing 42 secured in the frame 1 and collars 43 are secured by set screws 44 to the journal 41 at each end of the bearing 42. Thus by loosening the set screws 44, the journal 41 may be adjusted longitudinally in its bearing to the required extent.

The grooved rolls 20 and 25 are so adjusted and set in their lateral position that the belt runs passing through the groove thereof are brought into close proximity to the adjacent belt runs, as shown in Fig. 3. Preferably the pair of belt runs do not touch each other or run so close that the edges of the slivers

carried thereby are caught or pinched between the two belt runs although in some cases the edges may run in contact.

With the machine thus constructed, the two slivers carried by each pair of belt runs thus brought into close proximity are together taken off by the single bank of condensing aprons and rolled together and condensed thereby into a single roving. As shown in Fig. 1, for example, each pair of slivers carried by the adjacent belt runs diverging upward from the dividing roll 2 are taken by the bank of aprons 4, 5 and condensed into the single roving 45 and all the rovings issuing from this bank of aprons 4, 5 are wound up on the jack spool 16. So also each pair of slivers carried by the belt runs diverging downward from the dividing roll 3 are taken by the bank of aprons 10, 11 and condensed into the single roving 46 and all the rovings issuing from this bank of aprons 10, 11 are wound up on another jack spool.

Thus a tape condenser embodying this invention is enabled with a set of tapes of a given width to bring the slivers carried thereby into pairs and form each pair into a single roving. The quality of the rovings is improved because of the doubling and mixing of the fibres which thus takes place, tending to equalize the quality. But the great advantage lies in being able to produce roving of twice the size that would be produced if the tapes acted in the usual manner.

In Fig. 6 there is illustrated one of the aprons such as 5 with the two slivers presented by the belt runs 35 and 37 being condensed into the single roving 45.

The grooved rolls employed for positioning one set of tape runs in close proximity to the other may be such as usually employed in a tape condenser because the tape runs which are not shifted laterally only run tangent to these rolls and may readily ride on the ridges between the grooves.

Other means than that already described may be provided for bringing the two belt runs into close proximity. For example, as shown in Fig. 4, the roll 47 having the position corresponding to the roll 21 and the roll 48 having the position corresponding to the roll 24 may be grooved and carry respectively in their grooves the belt runs 37 and 31, respectively, so that these sets of belt runs are moved by positioning laterally the rolls 47 and 48, in the manner already described, to bring the runs of each pair of tapes into the required close proximity.

The principle of the invention may also be applied to the deep grooved type of dividing roll condenser in which one tape is employed for each sliver, as illustrated diagrammatically in Fig. 2. In this case the intermediate banks of condensing aprons 49, 50, and 51, 52 are the ones which take the pair of slivers

and bring them together and condense them into single rovings. The dividing rolls 53 and 54 are provided at regular intervals with deep grooves so that in the well-known manner each tape carrying a sliver, viz., 55, 56, 57 and 58, is a single endless tape. The tapes 55 and 56 are brought into close proximity by suitable means, such as the lateral adjustment of the grooved roll 59 and in a similar manner, by the adjustment of the grooved roll 60, the tapes 57 and 58 are brought into close proximity.

While the slivers are illustrated as passing directly from the tape runs to the condensing aprons, it is to be understood that intermediate stripping rolls may be employed within the scope of the invention.

Having thus described the invention, what is claimed as new, and desired to be secured by Letters Patent, is:

1. A tape condenser comprising a pair of dividing rolls, a series of endless tapes engaging and laterally separated by said rolls with each of said tapes carrying away from said rolls on each of two diverging runs, a detached sliver, a pair of condensing aprons mounted adjacent the runs of all of the tapes which diverge in the one direction, and adjacent the sliver carrying portions of said tape runs to cause the slivers to be taken from all of said runs by said pair of aprons, a second pair of condensing aprons mounted adjacent the runs which diverge in the other direction, and adjacent the sliver carrying portions of said tape runs to cause the slivers to be taken from all of said runs by said pair of aprons and means for guiding the sliver carrying portions of the tape runs by pairs into close proximity as they pass the condensing aprons to cause the two slivers carried by said runs to be taken together and condensed into a single roving by the aprons.

2. A tape condenser comprising a pair of dividing rolls, a series of endless tapes engaging and laterally separated by said rolls with each of said tapes carrying away from said rolls on each of two diverging runs, a detached sliver, a pair of condensing aprons mounted adjacent the runs of all of the tapes which diverge in the one direction, and adjacent the sliver carrying portions of said tape runs to cause the slivers to be taken from all of said runs by said pair of aprons a second pair of condensing aprons mounted adjacent the runs which diverge in the other direction, and adjacent the sliver carrying portions of said tape runs to cause the slivers to be taken from all of said runs by said pair of aprons a grooved roll having its grooves engaging the runs of alternating tapes diverging in the one direction, a second grooved roll having its grooves engaging the runs of alternating tapes diverging in the other direction, and means for positioning the said grooved rolls to guide the sliver carrying

portions of the tape runs engaged by the grooves thereof into close proximity to the sliver carrying portions of the other runs as they pass the condensing aprons to cause the two slivers carried by each of said proximate runs to be taken together and condensed into a single roving by the aprons.

3. A tape condenser comprising a pair of dividing rolls, a series of tape runs engaging and laterally separated by said rolls with each of said tape runs carrying away from said rolls a detached sliver, a pair of condensing aprons mounted adjacent the tape runs which diverge in the one direction from the dividing rolls, and adjacent the sliver carrying portions of said tape runs to cause the slivers to be taken from all of said runs by said pair of aprons, a second pair of condensing aprons mounted adjacent the tape runs which diverge in the other direction, and adjacent the sliver carrying portions of said tape runs to cause the slivers to be taken from all of said runs by said pair of aprons, and means for guiding the sliver carrying portions of the tape runs by pairs into close proximity as they pass the condensing aprons to cause the two slivers carried by each said pair to be taken together and condensed into a single roving by the aprons.

30 4. A tape condenser comprising a pair of dividing rolls, two pairs of condensing aprons, two diverging series of tape runs, each series acting to carry separate slivers on each run of the series from the dividing rolls to one pair of the condensing aprons and means for causing the said slivers on each series of runs to be divided into groups with each group consisting of a plurality of adjacent slivers and the slivers of each group to be taken together and condensed into a single roving by the respective pairs of aprons.

In testimony whereof, I have signed my name to this specification.

HENRI BURHENNE.
